MILK BOTTLE WITH OPEN BOTTOM

Filed April 19, 1926

INVENTOR.

HOPKINS EVANS.

By, *Ralph Burch*
HIS ATTORNEY.

UNITED STATES PATENT OFFICE.

HOPKINS EVANS, OF TABER, ALBERTA, CANADA.

MILK BOTTLE WITH OPEN BOTTOM.

Application filed April 19, 1926. Serial No. 103,110.

This invention relates to extremely new and useful improvements in bottles, and more particularly to those which are used to contain, and in which to transport milk, and the object of my invention is to construct a bottle which, having a detachable bottom, will permit of perfect cleansing and thereby render the same highly sanitary.

A further object is to produce a bottle with an open bottom so that a current of air may circulate through the same, thereby purifying it to the utmost extent.

A still further object is to construct a bottle, the interior of which has no angular corners, thus reducing the possibility of corrosion to a minimum.

Other objects and many of the attendant advantages should be readily appreciated as the same becomes better understood by reference to the accompanying drawings in which:

Fig. 1 is a perspective view of this improved bottle.

Fig. 2 is a vertical section through the center of the bottle.

Fig. 3 is a vertical section through a modified form of this invention.

And Fig. 4 is a fragmentary sectional view of a further modified form.

Referring more in detail to the drawings in which similar reference numerals designate the corresponding parts throughout the several views it will be seen that

The numeral 6 designates the main body of the bottle, the side walls of which terminate as at 7, thereby rendering the bottle bottomless, and adapted to receive a plug or the like.

The lower interior surface of the sidewall 6 is provided with threads 8 and is recessed to an extent to provide a surface 9 which will frictionally lock with the relatively disposed surface 10 of the plug 11, thereby preventing any leakage of the contents from the bottle. To assist in tightening or loosening of the plug, the exterior radial surface 13 of the same is serrated or knurled to facilitate gripping.

In the preferred embodiment of this invention as illustrated in Fig. 2 the upper surface 12 of the plug 11 or the surface adapted to form the interior bottom of the bottle, is concaved, to eliminate any angular corners and thereby reduce the possibility of corrosion.

The modified form of this invention as disclosed in Fig. 3 is of much simpler construction, however, the principle is the same as will be obvious, the threads 8 are adapted to receive the relatively threaded plug 11, but the frictional locking surfaces are somewhat removed, being established by the coniction of the lower sidewall surface 14 of the bottle and the upper surface 15 of the gripping flange 13 of the plug.

In the further modified form, Fig. 4, a somewhat different construction is employed to seal the open bottom of the bottle, the threads 16 being produced in the lower exterior surface of the bottle sidewall 6 and adapted to receive the relatively threaded cap member 17 and to eliminate all possibility of leakage from the bottle, a suitable washer 18 or the like is adapted.

It will be obvious from the foregoing description that this invention is a great improvement in bottle construction and more particularly to bottles adapted to contain and in which to transport milk, and while the preferred embodiments of the invention have been disclosed it is to be understood that minor changes in the details of construction, combination and arrangement of co-operating elements may be resorted to within the scope of what is claimed without departing from the spirit of the invention.

What is claimed is:—

1. A milk bottle comprising a body having an open bottom provided with interior screw-threads, said threads being recessed relative to the interior wall of said body providing a radial surface at the end of the threads, and a plug having exterior screw-threads recessed relative to the outer periphery of the plug, adapted to threadedly engage the threads of said body, whereby an

even joint is effected between the inner walls of the plug and body.

2. A milk bottle comprising a body having an open bottom, provided with interior screw-threads, substantially recessed relative to the interior wall of said body and a plug having its upper central portion concaved and surrounded by an exteriorly screw-threaded flange, off-set inwardly

from the outer periphery of the plug and adapted to threadedly engage the threads of the body, whereby an even joint is effected between the inner walls of the body and plug.

In testimony whereof I affix my signature.

HOPKINS EVANS.
